UNITED STATES PATENT OFFICE.

JOHN F. MCGUIRE AND ARCH H. HARRIS, OF AKRON, OHIO, ASSIGNEES OF ONE-THIRD TO CHARLES C. GOODRICH, OF SAME PLACE.

KNIFE OR SHEARS SHARPENER.

SPECIFICATION forming part of Letters Patent No. 628,021, dated July 4, 1899.

Application filed November 16, 1898. Serial No. 696,591. (No model.)

To all whom it may concern:

Be it known that we, JOHN F. MCGUIRE and ARCH H. HARRIS, citizens of the United States, residing at Akron, in the county of 5 Summit and State of Ohio, have invented a certain new and useful Improvement in Knife or Shears Sharpeners, of which the following is a specification.

Our invention has relation to improvements 10 in devices for sharpening knives, shears, and scissors; and the object of our invention is to provide a neat and compact machine adapted to be readily secured to and removed from a table or shelf and by which an unskilled person 15 may accurately sharpen such articles; and its further object is to cause the stone to operate upon the blade with a compound sliding elliptic motion.

To the aforesaid purpose our invention consists 20 in the peculiar and novel construction, arrangement, and combination of parts hereinafter described and then specifically pointed out in the claims, reference being had to the accompanying drawings, which form a part of 25 this specification.

In the accompanying drawings, in which similar reference-numerals indicate like parts 30 in the different views, Figure 1 is a front elevation, and Fig. 2 a side elevation, of our improved machine.

Referring to the figures, 1 is a vertical post forked or slotted at the top to form guides 2, provided with bosses 3 4 to form abutments for wheel-hubs and turned at a right angle 35 at the bottom, where it is provided with a thumb-screw 5. The lower back part of this post is reinforced with a web 6 to afford strength. From the front of the post extends a horizontal arm 7, the outer end of which is 40 turned upward parallel with the post 1 and ends in a peculiarly-formed head 8. Journaled on a wrist in the boss 3 is a spur-wheel 9, held by a cap-screw and provided with a handle 10, which meshes in a pinion 11, similarly 45 retained on a short shaft 12, that runs in a bearing in the boss 4. On the opposite end of the shaft 12 is a disk-wheel 13, bearing a wrist provided with a clamp 14, that grips the lower end of the stone 15, the upper end 50 of the stone being held by a clamp 16 on a slide 17, that moves in the guides 2.

The head 8 has the upper face beveled at the proper degree to hold the blade of the shears or scissors to the stone, and this face has a number of grooves to rest the back of 55 the knife in when its edge is subjected to the stone, a number being provided to adapt the machine to different widths of blades.

Having thus described our invention, what we claim, and desire to secure by Letters Patent, is—

1. In a knife and shears grinder the combination with a supporting-post, of a stone connected therewith having one end adapted to move reciprocally lengthwise, and the other 65 to move in a circle, and mechanism such substantially as shown to impart motion to said stone, substantially as shown and described.

2. In a knife and shears grinder the combination with a stone having one end adapted 70 to move reciprocally lengthwise and the other to move in a circle, of a supporting-head adjacent to said stone, and beveled to hold a shears-blade at a definite angle to said stone, substantially as shown and described.

3. In a knife and shears grinder the combination with a stone having one end adapted to move reciprocally lengthwise, and the other to move in a circle, of a supporting-head adjacent to said stone having grooves to receive 80 the back of the blade to be ground, substantially as shown and described.

4. The herein-described grinding-machine consisting of a supporting-post, a clamp to retain it, a clamp arranged to slide in ways 85 in said post and adapted to clamp one end of a stone, a shaft mounted in said post bearing a pinion and crank-head, a clamp pivoted in said crank-head and adapted to grasp the opposite end of said stone, a driving-gear to 90 turn said pinion, and a supporting-arm bearing a head adjacent to said stone beveled toward said stone and having in its upper face grooves parallel with the face of said stone, substantially as shown and described.

In testimony that we claim the above we hereunto set our hands.

JOHN F. MCGUIRE.
ARCH H. HARRIS.

In presence of—

C. P. HUMPHREY,
C. E. HUMPHREY.
